UNITED STATES PATENT OFFICE

ROBERT A. STEVENSON, OF WILMINGTON, DELAWARE

COMBINED LIFTING AND CARRYING TOOL

Application filed May 3, 1930. Serial No. 449,484.

The present invention relates to a combined tool for lifting and carrying either a single or a plurality of containers, said containers being characterized structurally as having a laterally extending exterior flange or extension located adjacent the upper end of the container.

More specifically, the invention is particularly adapted for use in handling either a single or a plurality of ice cream cans or the like.

Centralized manufacture of ice cream and frozen products usually entails packing the products in large cans for cold storage and delivery to points of consumption or distribution. A considerable volume of material is so handled in cans relatively large and difficult to manipulate by the hands of workmen. The material is usually maintained in frozen condition by refrigeration, at points where retail sales are made by cabinets having open compartments into which the filled cans are inserted, until the contents are used. These compartments are only slightly larger than the container to be received therein and the containers are generally lowered well below the top of the cabinet to allow for accommodation of a closure member, necessitating a tool in the hands of an attendant to place and remove cans. Various grips have been employed for handling the cans such as pliers, tongs and the like. The present invention contemplates a unitary structure which may be employed both in placing and removing the cans, and which is also adapted for use in carrying simultaneously a plurality of cans either empty or loaded, thus saving time and expense in the handling operation and avoiding the use of more than one tool.

The invention has for its object the provision of a combination tool which may be used to lift and carry a plurality of cans or to manipulate a can or container which may be placed in a relatively restricted space.

A further object of the invention is the pro-

vision of a sturdy yet compact structure which can be economically manufactured. Further objects and advantages will become apparent to those skilled in the art, from the structure hereinafter described and claimed and shown in the drawing forming a part of this specification.

Referring to the drawing:

Figure 1 is a plan view of a preferred form of the device in accordance with the invention.

Fig. 2 is an elevational view taken at a right angle to the showing of Fig. 1.

Fig. 3 is a sectional view taken on line 3—3 of Fig. 2.

Fig. 4 is a cross sectional view through the main body portion taken on the line 4—4 of Fig. 1.

Fig. 5 is a view illustrating the depending jaw in lifting position for removing a can from a container.

Fig. 6 is an illustration of the device of the invention in engagement with a plurality of cans.

Fig. 7 shows a modified form of device without the depending jaw.

Fig. 8 is a side view of the device of Fig. 7.

Fig. 9 is a cross section taken on line 9—9 of Fig. 7.

Fig. 10 is a cross section taken on line 10—10 of Fig. 8.

Fig. 11 is a modified form showing separate lugs.

Referring particularly to the preferred form of the structure, Fig. 1 of the drawing, 1 represents generally a tool structure in accordance with the invention. The structure consists of an integral casting or forging having a handle portion 2 which is suitably formed to fit without discomfort the hand of the user and to provide means for manual manipulation of the tool. A pair of converging connecting arm portions 3 extend downwardly from ends of the handle portion to a position underneath the handle 90

connecting with a plurality of spaced parallel gripping jaws 4 and 5 and a lateral offset depending jaw member 6. The jaw members 4 and 5 are structurally identical and are disposed facing outwardly in spaced relation on opposite sides with respect to a vertical center line taken through the structure. Each jaw comprises a portion 7 extending longitudinally of the structure, having at its upper end a downwardly extending holding lug 8, and terminating at the lower end in an angularly disposed outwardly directed hook 9 presenting a surface suitably arranged to engage below an external bead or extension on a can when the upper lug is in engagement with the inner edge surface of the top of the can. The hook 9 is arranged to engage an extended surface of the underside of the can bead or extension whereas the lug 8 is relatively narrow and makes what may be termed only a point contact on the inside of the can. This is an important feature which avoids extended contact with material within the can, even though such material extend flush with the upper edge of the can or container. The upper point or lug 8 of the jaw is laterally offset from the main portion 7, defining in conjunction therewith a recess 10 between the inner face of the lug and the main body portion. The upper edge of a container gripped by the jaw extends into the recess between the main body portion and the lug.

The jaw portions 4 and 5 have their respective lugs and hook portions disposed at the same elevation but the depending jaw 6 is laterally offset midway between the jaws 4 and 5 and disposed well below said jaws. To afford the offset position, the jaw 6 is supported by an extension 11 from the center web 12 of the main body portion. The extension 11 is directed downwardly and outwardly and terminates at its outer end in the depending jaw 6. This depending jaw 6 is similar in structure to the previously described jaws 4 and 5, having identical hooked end and spaced lug features for gripping a single can. The depending jaw, however, has its gripping elements well below those of the other jaws and laterally disposed 90 degrees to avoid interference with the lifting functions of the other jaws when handling a plurality of cans. A strengthening rib 14 is indicated as connecting the central web of the main body portion and the extension 11, for the purpose of lending rigidity to the structure and to minimize the amount of metal necessary for the manufacture of the device. To this end, the converging arms of the structure and the body portions of the jaw members may be provided with the marginal ribs 13 which serve to materially strengthen the structure.

Referring in particular to Fig. 5 of the

drawing, the tool is shown in the position of engagement with a can 15, within a cabinet 16. It will be noted that in the normal position of these cans within a refrigerating container that the upper edge of the can is lowered well below the top of the cabinet and provides but little space between the sides of the can and the cabinet. The lower or depending jaw 6 is employed for the purpose of lifting cans from confined spaces such as illustrated in this figure of the drawing and the provision of the depending jaw on the tool obviates the necessity of a workman carrying a separate implement for performing this function.

In Fig. 6 of the drawing, the tool is shown in gripping engagement with two cans for carrying or lifting the same. It will be noted that the cans are maintained in a parallel spaced relation when in engagement with the opposite jaws of the main body portion. In engaging the tool with the container, it is only necessary to cant the device so that the lower hook member passes under the flange or extension on the can with the lug 8 passing within the can to engage the inner surface thereof. This engagement can be obtained by either manipulating the tool or by tilting the can. The operation appears to be obvious from the showing in Figs. 5 and 6 of the drawing.

Referring in particular to Fig. 7 of the drawing, there is shown a tool for lifting and carrying simultaneously two containers. It will also be obvious that the device may be used with a single container. The structure is identical with the structure shown in Figs. 1 to 4 of the drawing, except that the depending jaw extension has been omitted. The lugs 8 and hooks 9 are arranged in an identical manner with that of the previously described structure and the oppositely disposed jaws are spaced by a connecting web which does not continue to form an arm extension.

The devices shown in Figs. 7 to 10 are employed chiefly merely for handling and carrying the loaded or empty containers, it being obvious that in factories or where it is not necessary to handle containers which are in confined spaces, that the lower or depending jaw is not essential to the structure.

While the structures have been shown in the form of integral castings, it is obvious that the lugs 8 may be in the form of separate members inserted in slots in the main body portion and riveted or spot-welded therein. It will also be apparent that the handle portion can be provided, if desired, with an insulating handle structure. This may be of advantage where the tool is used for long periods of time in refrigerated spaces where the metal is liable to become extremely cold. Such handle structures as

are referred to are conventional in the art and are not shown on the drawing.

The structure shown and described above has the advantage of being formed as an integral casting and structurally arranged to be very rugged and compact. It also has the advantage of economy in manufacture, providing a device which may be cheaply made but which eliminates the use of separate tools yet allows a workman to carry in each hand a plurality of loaded or empty containers and permits that workman to have embodied in the tool a gripping jaw which may be utilized in removing and replacing containers within cabinets and the like. This is a distinct advantage over the prior art.

Having thus described my invention in accordance with the statutes, I claim:

1. In a tool for handling simultaneously a plurality of containers having annular projections adjacent their upper ends, an integral rigid structure comprising a handle and main body portion and a plurality of spaced oppositely disposed jaw members, each jaw including a hook for engaging the annular projections on the containers and a lug spaced from the hook adapted to engage the inner upper surface of the container.

2. In a tool for handling simultaneously a plurality of containers having annular projections adjacent their upper ends, an integral rigid structure comprising a handle, a pair of spaced oppositely disposed rigid jaws in spaced relation underneath the handle, and a reinforcing web connecting the spaced jaws.

3. In a tool for handling simultaneously a plurality of containers having annular projections adjacent their upper ends, an integral rigid structure comprising a handle, a pair of spaced oppositely disposed rigid jaws in spaced relation underneath the handle, a reinforcing web connecting the spaced jaws, and a separate depending jaw rigidly connected with the reinforcing web and disposed below and in offset relation to said pair of jaws.

4. In a tool of the character described, a pair of oppositely disposed rigid jaw members, a spacing and reinforcing member connecting said jaw members, and a handle overlying the jaw members and connected therewith, each of said jaw members including a rigid hook for engagement beneath an annular projection on a container and a rigid angularly disposed lug spaced from said hook adapted to engage within the upper end of the container.

5. In a tool of the character described, a pair of oppositely disposed rigid jaw members, a spacing and reinforcing member connecting said jaw members, a handle overlying the jaw members and connected therewith, an outwardly and downwardly directed extension connected with said reinforcing

member, and a separate depending jaw at the lower end of said extension.

6. In a tool of the character described, a handle, a pair of spaced rigid jaws beneath said handle, a separate depending jaw positioned below and laterally offset with respect to the first mentioned jaws, said depending jaw having its upper end angularly extended between said pair of jaws to serve as a spacing connection and reinforcement for said jaws.

In testimony whereof, I have hereunto subscribed my name.

ROBERT A. STEVENSON.
